M. J. OTTO,
HOT AIR FURNACE,
APPLICATION FILED OCT. 1, 1919.

1,380,734.

Patented June 7, 1921.

UNITED STATES PATENT OFFICE.

MAXIMILIAN J. OTTO, OF NEW YORK, N. Y.

HOT-AIR FURNACE.

1,380,734.

Specification of Letters Patent. Patented June 7, 1921.

Application filed October 1, 1919. Serial No. 327,712.

To all whom it may concern:

Be it known that I, MAXIMILIAN J. OTTO, a citizen of the United States, residing in the borough of Manhattan, city, county, and 5 State of New York, have invented a new and useful Improvement in Hot-Air Furnaces, of which the following is a description.

This invention has reference to hot air 10 stoves or furnaces and, particularly, to stoves adapted to give heat through the medium of gas or oil, and convey the same to either the floors above or to radiate its heat in the room in which the stove stands 15 through the medium of long lengths of heat conducting pipes.

Among the objects of my invention may be noted the following: to provide means by which hot air generated in a small, cylindrical gas or oil stove may be conveyed to, 20 and distributed in, one or more rooms above that in which the heater stands and at the same time have the hot air generated tempered by moisture commingled with the hot 25 air and reduced by the latter to a gaseous, invisible fluid; to provide means by which hot air, generated in a gas or other fuel burner, may be conveyed to different parts of the room in which the heater stands and 30 tempered by the admixture with the hot air of a moist vapor; to provide means by which a hot air furnace may produce its own moisture-laden heat and conduct the same to distant points, as may be required; and to 35 provide a simple, economical, cheaply constructed, efficacious device by means of which the foregoing objects may be accomplished, together with others which will be pointed out during the course of this description.

40 In order that my invention may be clearly understood, I have provided drawings wherein:

Figure 1 is a sectional elevation of a hot air stove or furnace constructed and 45 disposed in accordance with my invention; and

Fig. 2 is an elevation showing a structure wherein the heat generated may be radiated into the room in which the heater stands and at the same time distributed to distant 50 points in the same room through the medium of radiating pipes or coils, the latter being broken at several points owing to the limitations of the sheet.

Referring to the drawings, the numeral 1, 55 in Fig. 1, indicates the floor of a room or cellar in which the heater may be set or

erected, 2 being the ceiling, and also the floor of one or more rooms above, in which registers or radiators, conventionally shown at 3, may be set in any suitable manner for 60 the purpose of conveying the heat directly to the room or rooms above. The small heater, the cylindrical casing of which is indicated by 4, may be of any acceptable or suitable type, such as, for example, that 65 shown in my Patent No. 1,312,804, granted Aug. 12, 1919, and in which heat conducting tubes 5 are located to convey the heat from the burner 6 directly to a chamber 7. The cylindrical casing 4 may be perforated or 70 provided with openings 8, in order that the heat generated by the burner may, in some measure, be radiated into the room in which the heater stands. The heating medium, or 75 coil 6, may be a gas burner or oil burner; but, in the instance shown, it is a gas burner of the type shown in my said patent connected to a source of supply by the pipe 9, the supply to the stove being controlled by the cock 10. At the bottom of the cylindrical casing 4, a perforated heating plate 11 is provided through which the heat from the 80 burner may enter the casing and be radiated from the latter into the room in which the stove stands, and the heat from the burner 85 is also conveyed directly through the tubes 5 into the chamber 7 above. The chamber 90 7 is provided in a frusto-conical casing or drum 12, the base of which is closed, as at 13, and has a downwardly extending flange 95 14 fitting within the top of the drum 4. The base 13 rests upon an outturned flange 15 at the top of the casing 4, thus giving a solid and substantial seat and connection 100 between the hot air drum 12 and the cylindrical casing 4; but, it will be understood that the hot air drum 12 can readily be lifted and removed from the cylindrical casing 4, when desired. The cylindrical casing, at the top of the tubes 5, is provided 105 with a perforated diaphragm 16 through which the heat from the casing 4 may also enter the chamber, and which aids in supporting the tubes.

The drum 12 is apertured at a plurality of 110 points near its top, in which are set heat conducting pipes 17 extended in any suitable direction, but preferably always tending upwardly, to connect with the radiators 3. At some point in the pipes 17, dampers 18 are provided, preferably located as shown, for the reason presently described. The top

of the drum 12 is perforated, as at 19, and below the same is provided with a damper 20 also correspondingly perforated, said damper being adapted to rest upon the flange 5 or collar 21 and to be shifted circularly to close or open the apertures extending through the same and the top of the drum 12, so as to control the passage of the heat in the chamber 7 to the bottom of the steam 10 or water boiler 22, which is adapted to set on the top of the drum 12 and have the water therein heated to produce steam. A heavy cover 23 is applied to the steam boiler or chest, and the latter, near its top, 15 is provided with outlet pipes 24 connected by sliding sleeve couplings 25 to short pipes 26 tapped into the pipes 17. The dampers 18 are preferably located above the point of generation and admission of steam, since, 20 when the heat is cut off and steaming may continue, the steam should be cut off from the radiators by turning the dampers 18.

From the foregoing description, it will be seen that my hot air furnace comprises 25 an ordinary, small, sheet-iron, cylindrical heater, such as is usually used for oil or gas burners, and which is portable and seldom more than $2\frac{1}{2}$ feet high, and 12 to 18 inches in diameter, and my invention consists in 30 the adaptation of such a heater or burner to the heating of large rooms or spaces as set forth above and shown in Fig. 1 in an economical, rapid, effective manner, and without the usual accompaniment of stationary hot air furnaces, such as dust, dirt, soot 35 and dry air, and I have found that my small cylindrical heater covered by my aforesaid patent, when combined with the means shown in Fig. 1, as well as in Fig. 2, produces an exceedingly effective furnace which 40 will thoroughly heat not only the room in which it stands, but one or more rooms above or adjacent the same, and by combining a steam drum or tank therewith and 45 connecting the same to the hot air flues, the air is moistened quite effectively, thus eliminating the objection to the usual hot air furnaces, which produce dry, vitiated air 50 which is quite objectionable from many standpoints, as is well known.

In Fig. 2, I have shown an embodiment of my invention adapted for heating very effectively unusually large rooms, even to the far corners, as may be desired. In this embodiment of my invention, the cylindrical heater or casing 27 may be of unperforated sheet iron, the heat from which will radiate into the room in which the heater stands. The hot air drum or chamber 12 has a plurality of pipes 17 connected therewith, and said pipes are connected with pipe exten-

sions or coils 28, which may be as extensive as desired and carried to any point or position in the room. The heater is shown as set, for example, in a hearth or fire-place 65 29, and a part of the pipe or coil 28 is shown as coupled with an extension 30 tapped into the chimney, as at 31. The other features of the furnace are the same as in Fig. 1, and such features are respectively, indicated by 70 like numerals. With this embodiment of my invention, I am able to extend the coils or pipes 28 into any part of the room in which the heater stands or in the rooms above, if desired, thus effectively heating 75 said rooms even to the far corners.

It will be readily understood that, when the steamer is not required, it may be disconnected by sliding the couplings 25 to one side so as to release the pipes 24, or the reverse so as to release the pipes 27, and the steamer may then be lifted from the drum 12. On the other hand, when it is desired to eliminate the steaming feature or reduce 80 the quantity of the same, the damper 20 may 85 be closed. When it is desired to cut off the heat from any of the pipes 17, this may be done by closing the dampers 18.

Having thus described my invention, what I claim and desire to secure by Letters Patent is:

1. A hot air furnace comprising a cylindrical heating member having mounted thereon a hot air drum; means for generating heat at or near the bottom of the said member; means for conveying the heat to the hot air drum; a steam drum mounted on the hot air drum; a damper interposed between the steam drum and the hot air drum; conduits extending from the hot air drum; conduits extending from the steam drum; and means for coupling the two conduits, whereby the hot air from the air drum and the steam from the steam drum may be commingled and distributed. 95

2. A hot air furnace consisting of a cylindrical casing; a source of heat arranged at the bottom of the casing; a drum or chamber mounted on the top of the casing; a plurality of heat conveying tubes extending between the source of heat and the drum; a plurality of conduits tapped into the drum for conveying the heat thereof to distant points; a steam drum mounted on the hot air drum; a coupling extending from said 100 steam drum to the hot air conduits whereby to mix steam with the hot air emanating from the hot air drum; means whereby the steam drum may be demounted from the hot air drum; and means whereby the said 105 coupling may be detached.

MAXIMILIAN J. OTTO.
